CLAIM

The ornamental design for a food container, as shown and
described.

DESCRIPTION

FIG. 1 is a top right side perspective view of a food container
showing my new design.

FIG. 2 is a top plan view thereof.

FIG. 3 is a front elevational view thereof.

FIG. 4 is a right side elevational view thereof.

FIG. 5 is a left side elevational view thereof.

FIG. 6 is a rear elevational view thereof; and,

FIG. 7 is a bottom plan view thereof.

The broken lines represent portions of the food container
that form no part of the claim.

1 Claim, 5 Drawing Sheets
